UNITED STATES PATENT OFFICE.

EDWIN W. SMITH, OF BEVERLY, MASSACHUSETTS, ASSIGNOR TO UNITED SHOE MACHINERY CORPORATION, OF PATERSON, NEW JERSEY, A CORPORATION OF NEW JERSEY.

SPLITTING-MACHINE.

1,334,323.

Specification of Letters Patent. Patented Mar. 23, 1920.

Application filed October 24, 1918. Serial No. 259,577.

To all whom it may concern:

Be it known that I, EDWIN W. SMITH, a citizen of the United States, residing at Beverly, in the county of Essex and State 5 of Massachusetts, have invented certain Improvements in Splitting-Machines, of which the following description, in connection with the accompanying drawings, is a specification, like reference characters on the 10 drawings indicating like parts in the several figures.

This invention relates to cutting machines and is herein illustrated as embodied in a machine for producing rands and welts, for 15 skiving taps and for preparing various articles for use in the manufacture of boots and shoes.

In splitting a strip of stock diagonally from corner to corner to produce rands or 20 in splitting a strip by a cut extending from a point spaced from one corner to a point spaced equally from the diagonally opposite corner to produce welts, machines have been employed in which the strip is forced 25 against an inclined knife by two rolls, the knife being connected with one of the rolls in such manner that the extent of its inclination depends upon the extent to which the rolls are separated by the stock. Machines 30 for performing this operation are usually provided with a stripping knife so that in a single operation a strip is cut from a sheet of stock and the strip split on an angle as has been described above. Commonly an 35 edge gage is provided the position of which determines the width of the strip. In such a machine the strip is progressively cut off and guided between the edge gage and the stripping knife to the feed rolls and the 40 splitting knife. It is desirable that the axis of angular movement of the splitting knife should register with the longitudinal center line of the strip so that, whatever the variation in thickness of the strip, it shall be split 45 into two equal portions. Hitherto this alignment of the axis of angular movement of the splitting knife with the longitudinal center line of the strip has been strictly possible for only one width of strip; and when a 50 strip of a different width was to be operated upon, the splitting knife has been bodily adjusted upwardly or downwardly to bring its axis of angular movement, as nearly as is possible by such adjustment, into alignment 55 with the center line of the strip. Although

such an adjustment will serve practically for splitting strips which do not vary greatly in width, the error involved will increase in proportion to the extent to which the strips to be split differ in width so that 60 a machine which is built to split a strip of medium width accurately into two equal parts of triangular or trapezoidal outline in cross-section will not split accurately strips which are very wide or very narrow. 65

One object of the present invention is to provide a relative bodily adjustment between the knife and the guiding means for the strip such that the axis of angular movement of the knife may be brought into alignment with the center line of strips of different widths. In the illustrative machine the splitting knife carrier is bodily adjustable widthwise of the strip, to bring about the desired relation between its axis and the center line of the strip. 75

This and other objects of the invention will be described as embodied in an illustrative machine and pointed out in the appended claims. 80

Referring to the accompanying drawings,—

Figure 1 is a plan of a machine in which the present invention is embodied;

Fig. 2 is a side elevation;

Fig. 3 is a rear elevation;

Fig. 4 is a cross-section on the left-hand section line of Fig. 2;

Fig. 5 is a perspective showing a sheet of stock being operated upon by the two knives; 90

Fig. 6 is a perspective of the splitting knife and its mounting, and

Fig. 7 is a cross-section on the right-hand section line of Fig. 2.

The illustrative machine is similar in its mode of operation to that of the machine of Patent No. 1,025,556, granted May 7, 1912. A sheet of stock 100 such as leather is fed by an upper feed roll 1 on the rotatable shaft 3 and a lower feed roll 4 on 100 the rotatable shaft 5 to a stripping knife 7 which cuts a strip from the sheet and to an inclined knife 9 which splits the strip on an angle. The cut of the knife 9 may extend diagonally from corner to corner of the 105 strip to form two rands or, as shown in Fig. 5, diagonally from a point spaced from the upper right-hand corner to a point similarly located with respect to the lower left-hand corner to form two McKay welts. 110

The two feed rolls are movable toward and from each other and are compelled to move equally in opposite directions. The upper shaft 3 is mounted in bearings in a casting 11 having rearwardly extending arms 13 the hubs of which are fast to a rock-shaft 15; and the lower shaft 5 is similarly mounted in bearings in a casting 17 having rearwardly extending arms 19 the hubs of which are loose on a rotating shaft 21 located below the rock-shaft 15. In order to urge the feed rolls at all times toward each other as well as to compel movement of one roll to cause equal movement of the other in the opposite direction, the casting in which the bearings of the shaft 3 are formed has a projecting arm 113 (see Figs. 1, 2 and 3) which extends rearwardly, then downwardly and then rearwardly again; and the casting in which the bearings of the shaft 5 are formed has an arm 119 which extends rearwardly, then upwardly and then rearwardly again. A coiled spring 23 is under tension between the rearmost portions of these arms 113 and 119 tending at all times to separate such portions and thereby to cause the feed rolls to approach each other. A rod 25, the threaded ends of which extend freely through perforations in the ends of the arms 113, 119, passes through the coiled spring. Nuts 27, 29 on the ends of the rod contact with the arms and limit the extent of their separation. The vertically extending portions of each of the arms 113, 119 has formed thereon inclined rack-teeth (see Figs. 1 and 3) with which meshes a bevel pinion 30, said pinion being freely revolvable on a pivot carried by the frame of the machine. When the feed rolls are separated or caused to approach each other, the extent of their movements is thus always equal, the purpose of this construction being to maintain the center of the leading end of the strip of stock in the plane which contains the axis of angular movement of the splitting knife 9 irrespective of variations in thickness of the stock as will presently be described more in detail.

The lower feed roll is driven directly from a large gear 37 on the driving shaft 39 which meshes with a gear 41 on the shaft 5 of the lower feed roll. The upper feed roll is driven from the lower feed roll by floating gears 45, 43 which mesh respectively with a gear 47 on the shaft 3 and a gear 49 on the shaft 5 as well as with each other. The shafts of the floating gears 45, 43 are connected with each other by links 51 and respectively with the shafts 3 and 5 by links 53, 55. With this construction the separation of the rolls 1 and 4 does not disturb the mesh of the driving gears.

The stripping knife 7 is adjustably clamped in a split holder by a pinch-bolt 57. The splitting knife 9 is slidably mount-

ed in a cylindrical holder 59, the bevelled sides of the knife being received in diametrically opposite V-shaped grooves in the holder. The longitudinal position of the knife in the holder is determined by a back-stop in the form of an arm 61 having a conical forward end which is received in a groove in the rear end of the knife, the hub of the arm being loosely mounted on a rod 63 and being engaged by a thumb-nut 65 threaded on said rod. The pressure of the work against the edge of the knife holds the knife against the stop, said stop being adjustable by means of the thumb-nut 65 to determine the longitudinal position of the knife. The cylindrical knife holder 59 is angularly movable about the central longitudinal axis of the knife, being thus movable in a stationary cylindrical carrier 67 having a slot 69 in the stem thereof to receive a screw-bolt 71 by which it is adjustably fastened in vertical position to a bracket 72 which is in turn horizontally adjustable on the frame of the machine and held in adjusted position by a screw-bolt 74, said bolt passing through a slot 76 in the bracket 72.

In order to cause angular movement of the splitting knife to take place in accordance with the extent of separation of the feed rolls, and consequently in accordance with the thickness of the stock, a yoke 75, clamped to the knife holder 59 by a pinch-bolt 76 is provided with teeth which mesh with similar teeth formed on one end of the horizontal arm of a bell-crank lever 81 pivoted to the frame of the machine at 83 and having at the upper end of its vertical arm a roll. This roll is received in a slot 87 formed in a disk 89 which is fastened to the casting in which the bearings of the upper feed roll shaft is mounted by screw-bolts 91, the stems of which pass through arcuate slots 93 in the disk and are threaded into the casting. It is thus possible to adjust the disk angularly and by changing the angular inclination of the slot 87 to determine the extent of angular movement which is imparted to the splitting knife 9 by a given extent of bodily movement of the feed rolls.

In machines of this general type in which a pair of feed rolls and an angularly movable knife are employed it is desirable that the edge of the knife be spaced considerably from the bite of the rolls so as to provide for a considerable extent of angular movement of the knife. To this end the feed rolls are provided with a series of parallel grooves 95 into which extend suitably shaped projections on pressers 97, 99, said pressers extending rearwardly from the bite of the rolls 125 into close proximity to the edge of the knife. The presser 97 is provided with a stem which passes up through a bore in the casting by which the upper roll is carried and is urged downwardly at all times by a spring 103, 130

the limit of its downward movement being determined by nuts 105 threaded on the stem. The mounting of the lower presser is similar to that of the upper and will not be described in detail. In order to provide for feeding the last portion of the stock to the knife a pusher 109 is provided which extends up through a slot in the table 110 and is supported adjacent the feed rolls on the upper end of a rod 117 which is urged upwardly into the position shown by a spring 119 but may yield in opposition to the force of the spring. Normally the pusher occupies the position shown. When, however, a piece of stock is placed upon the table 110 and presented to the feed rolls, the pusher is forced down and reciprocates continuously beneath the stock until the rear end of the stock is close to the bite of the feed rolls. At this time on one of its back strokes the pusher rises, engages the end of the stock and feeds the last portion thereof to the knife, the driving mechanism of the pusher being constructed to impart the same rate of feed movement to the stock as do the feed rolls. The pusher is reciprocated from a crank-pin 121 (Fig. 7) mounted in a disk on the end of the shaft 21, said crank-pin entering an elongated socket 123 formed in one end of the pusher 109. In order to support this end of the pusher a link 125 is pivoted at its lower end to the frame of the machine by a properly shaped screw-bolt 127 and at its upper end to the pusher by a similar screw-bolt 129. The shaft 21 is rotated from the gear 37 which meshes with a gear 131 fast to said shaft.

In the operation of the machine a sheet of stock is presented to the feed rolls with one of its side edges in engagement with an edge gage 133. As the stock is fed through the machine, the knife 7 cuts from it a strip the width of which is equal to the distance from the edge of the knife 7 to the face of the edge gage, and the knife 9 splits the strip diagonally. The edge gage 133 has a slotted tail (see Fig. 1) through which passes a screw-bolt 135 by which it is adjustably held in position. As shown in the drawings, the position of this gage is such that the axis about which the splitting knife 9 is angularly movable is located midway between the operative face of the gage and the edge of the trimming knife 7; and the axis of the splitting knife consequently coincides with the center line of the strip which is cut off. When this gage is adjusted so as to cause a narrower strip to be cut off and the splitting knife is angularly adjusted, by loosening the pinch-bolt 76 and turning the holder 59 in its carrier 67, to cause the narrower strip to be split diagonally from corner to corner (or from a point spaced from one corner to a point equally spaced from the diagonally opposite corner) the axis of angular move-

ment of the knife will be somewhat to the left (as viewed in Fig. 3) of the center line of the strip. Hitherto the vertical adjustment of the carrier 67 has been depended upon to correct the inaccuracy with sufficient precision, but in the present construction a horizontal adjustment of the carrier 67 is possible by reason of the mounting of the stem of the carrier on the horizontally adjustable bracket 72. In order to permit this horizontal adjustment without disturbing the mesh of the teeth on the end of the horizontal arm of the bell-crank lever 81 with the teeth on the yoke 75, said horizontal arm is made in two parts (see Fig. 1) one of which is slotted; and the two parts are fastened together by a screw-bolt 137. The length of this horizontal arm may thus be increased when a narrower strip is to be split and decreased when a wider strip is to be split. With this construction it is possible to shift the axis of angular movement of the splitting knife horizontally and thus to maintain said axis in register with the center line of any given strip whether wide or narrow. The purpose of the provision for vertical adjustment of the knife carrier is principally to allow for inaccuracy in the manufacture of the machine or for wear of the parts. The extent of the vertical adjustment is small in practice and is usually permissible by reason of the loose mesh of the teeth on the parts 75 and 81. If necessary, however, the mesh of these teeth may be changed when the carrier 67 is adjusted.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

1. A machine of the class described, having, in combination, means for feeding a strip of stock, means for guiding the strip in its movement, a knife for splitting the strip on an incline, said knife being constructed and arranged to be moved angularly by the strip in accordance with variations in the thickness thereof, and means for producing relative adjustment between the knife and the guiding means to cause the longitudinal center line of the strip to register with the axis about which the knife moves.

2. A machine of the class described, having, in combination, means for feeding a strip of stock, means for guiding the strip in its movement, a knife for splitting the strip on an incline, said knife being constructed and arranged to be moved angularly by the strip in accordance with variations in the thickness thereof, and means for producing relative adjustment in two directions be-

tween the knife and the guiding means to cause the longitudinal center line of the strip to register with the axis about which the knife moves.

5. 3. A machine of the class described, having, in combination, an angularly movable knife, means for feeding a strip of stock to the knife comprising separable members the extent of separation of which controls the

10 angular position of the knife, means for guiding the strip by engagement with both edges thereof to the feeding means and the knife, and means whereby relative bodily adjustment between the knife and the guiding

15 means may be produced to bring the axis of angular movement of the knife into register with the center lines of strips of different widths.

4. A machine of the class described, having, in combination, means for feeding a strip of stock, an edge gage, a knife for splitting the strip on an incline, said knife being constructed and arranged to be moved angularly by the strip in accordance with variations in the thickness thereof, and means whereby the knife may be adjusted with respect to the edge gage to bring the axis about which it moves into line with the longitudinal center lines of strips of different widths.

30 5. A machine of the class described, having, in combination, means for feeding a strip of stock, a knife for splitting the strip on an incline, said knife being constructed and arranged to be moved angularly by the strip in accordance with variations in the thickness thereof, and means whereby the axis about which the angular movement of the knife takes place may be adjusted widthwise of the strip and at an angle to said

40 widthwise adjustment.

6. A machine of the class described, having, in combination, a pair of members for engaging a piece of stock, means for causing said members to move equally toward and from each other in accordance with a dimension of the stock at the point engaged, a movable knife, means responsive to the extent of separation of the members for controlling the position of the knife, and means whereby the knife may be adjusted bodily in two directions.

7. A machine of the class described, having, in combination, a pair of members for engaging a piece of stock on two sides to feed it, means for causing said members to

move equally toward and from each other in accordance with a dimension of the stock at the point engaged, a movable knife, means responsive to the extent of separation of the members for controlling the position of the knife, and means whereby the knife may be adjusted bodily in two directions.

8. A machine of the class described, having, in combination, a pair of members for engaging a piece of stock, means for causing said members to move equally toward and from each other in accordance with a dimension of the stock at the point engaged, an angularly movable knife, means responsive to the extent of separation of the members for controlling the position of the knife, and means whereby the knife may be adjusted bodily in two directions.

9. A machine of the class described, having, in combination, a pair of separable rolls for feeding a piece of stock, means for rotating the rolls, connecting means between the rolls constructed and arranged to compel them, when separated or caused to approach, to move equally in opposite directions, a knife, connecting means between the knife and one of the rolls for automatically varying the inclination of the knife in accordance with the extent of separation of the rolls, and means whereby the knife may be adjusted bodily in two directions.

10. A machine of the class described, having, in combination, means for feeding a piece of stock, a knife arranged to cut the stock on a bevel, and means including an extensible lever for connecting the knife with the feeding means to permit horizontal adjustment of the knife.

11. A machine of the class described, having, in combination, a pair of separable members between which the stock is fed, a splitting knife the inclination of which is controlled by the extent of separation of said members, and means for compelling the movements of said members to be equal in extent and opposite in direction, said means including two arms by which the separable members are carried, yielding means tending to move the arms toward each other, racks formed on said arms, and a pinion in engagement with the racks.

In testimony whereof I have signed my name to this specification.

EDWIN W. SMITH.
